UNITED STATES PATENT OFFICE.

GEORGE W. JACQUES, OF STRATFORD, CONNECTICUT, ASSIGNOR, BY MESNE ASSIGNMENTS, TO UNITED SHOE MACHINERY CORPORATION, OF PATERSON, NEW JERSEY, A CORPORATION OF NEW JERSEY.

DUPLEX FASTENER-SETTING MACHINE.

Application filed February 14, 1921. Serial No. 444,746.

To all whom it may concern:

Be it known that I, GEORGE W. JACQUES, a citizen of the United States, residing at Stratford, in the county of Fairfield and

5 State of Connecticut, have invented certain new and useful Improvements in Duplex Fastener-Setting Machines, of which the following is a specification, reference being had therein to the accompanying drawings.

10 This invention relates to fastener-setting machines and, in some respects, more particularly to machines of the type in which the work is clamped against a support by a presser foot. For the purpose of illustration the invention is herein disclosed as embodied in a duplex eyeleting machine adapted to operate simultaneously on two confronting work elements, as for example the quarters of a shoe-upper or the two complementary parts of a corset although the invention is not limited to machines of this type.

15 Machines of this type heretofore in commercial use have been provided with cooperative presser feet for pressing the two work elements against each other in advance of the fastener-setting locality, and their clamping pressure has been maintained continuously throughout the operation of the machine, not even excepting the periods during which the work is fed. Continuous pressure of the work elements against each other is, of course, desirable to prevent one from creeping relatively to the other, particularly in corset work in which any difference between the two work elements with respect to the length of their feeding movements would be multiplied many times because of the large number of feeding movements necessary to insert the required number of eyelets. On the other hand, when it is necessary to insert a single eyelet to replace one that has been set defectively, or to supply one where an accidental omission has occurred in the regular run of work, continuous pressure of the presser-feet is a detriment in that the eyelets previously inserted are likely to catch on the sides of the presser feet incidentally to the feeding operation. When they do catch, the work is

almost invariably damaged in one respect or another.

In view of the foregoing considerations an object of the invention is to provide a novel organization comprising cooperative presser members for pressing two work elements against each other in advance of the setting locality, and improved mechanism for separating them prior to and during the work-feeding period so that if either or both of the work elements carry previously inserted eyelets that would have to pass the presser foot locality such eyelets would be free to advance without likelihood of catching on either of the presser members. A feature of the invention consists in a novel combination by which a single actuator is utilized to operate the fastener-supplying mechanism and work-clamping means.

Other features of the invention are hereinafter described and claimed and are illustrated by the accompanying drawings in which,

Fig. 1, is an end elevation of a duplex eyeleting machine embodying the invention.

Fig. 2, is a front elevation looking in the direction of arrow 2 on Fig. 1.

Fig. 2^A, is a fragmentary elevation and plan of the hinge connection of the raceway and hopper.

Fig. 3, is a fragmentary detail of the raceway actuating and presser foot raising mechanism.

Figs. 4, 5, and 6, are detail elevations illustrating different relative positions of the punching and setting mechanisms and the presser foot.

Fig. 7, is a fragmentary elevation of the upper portion of the machine as shown in Fig. 2 illustrating a modified construction.

Fig. 8, is a fragmentary end elevation of the same construction, and,

Fig. 9, is a detail bottom plan of the raceway end and related parts.

Referring to Figs. 1 and 2, A represents a machine head which may be mounted upon a bench or other suitable support and which carries the operative portions of the machine. This head is provided with three upstanding bracket portions 1, 2, and 3.

brackets 2 and 3 carrying aligned bearings for a main operating shaft 4, and brackets 1 and 2 carrying two pairs of aligned bearing openings in which are pivot shafts 5 and 6 to which are fixed upper and lower lever or hammer members 7 and 8. The upper hammer member 7 is actuated by a cam lever 9, engaging a cam groove on one side of the cam 10 fixed on shaft 4, while the hammer 8 is actuated by a similar cam lever 11 actuated from a cam groove on the other face of the cam 10. At 12 is shown a downwardly inclined and forwardly projecting feed frame pivoted on an inclined axis, the bearings therefor being shown at 13 and 14 in Fig. 1. The forward end of the frame 12 carries, in aligned perforations therein, a pair of telescopically related punch and set mechanisms shown generally at 15 and 16, these mechanisms cooperating with a central anvil member 17 carried by a support 18 fixed at its rear end to the frame 12. This anvil member has setting surfaces thereon to cooperate with the oppositely disposed sets in a manner well understood in the art. Leaf springs 19 and 20, pivoted at 21 and 22 to the hammer elements 7 and 8, engage heads 23 and 24 of the punch and set mechanisms to retain the same normally in contact with the hammers by the rocking of which the punches and sets are caused to move toward the anvil element in proper time relation to punch the material and set eyelets therein. One side of the frame 12, as shown in Fig. 2, is provided with a pair of ears 25 and 26 between which is pivoted one end of a link 27. This link is pivoted at its other end 28 to a block adjustably fitted in a groove in a lever 29 pivoted in any suitable manner to the machine frame. The lever 29 carries a depending cam follower 30 which rides in a groove 31 in an edge cam 32 fixed to the shaft 4. The parts above described are substantially as shown in the Eames and Jacques Patent 1,434,688, granted November 7, 1922, and operate in substantially the same manner.

The bracket 2 carries at its upper end a laterally extending support 33 carrying at its outer end a bearing 34 for supporting a hopper 35, which is adapted to contain any suitable mechanism for agitating and discharging eyelets which pass out therefrom and into a pair of superposed raceway elements in a raceway 36. At 37 is shown a bracket for supporting an auxiliary eyelet supply reservoir 38 from which eyelets are fed by gravity to the hopper 35. Mechanism of this type is already well known in the art and hence no detail description thereof is deemed necessary in this application, as it forms no part of this invention.

At 39 is shown a spiral gear operatively connected to the mechanism within the hopper 35, and at 40 is shown a mating spiral

gear carried by a shaft 41. Shaft 41 is journaled in a bracket 42 fixed to the bracket 3, and carries at its outer end a friction wheel 420 which may be moved into contact with a mating wheel 43 carried on the shaft 4. At 44 is indicated a driving pulley over which passes a power belt 45, and at 46 is shown the usual handwheel. The pulley 44 is connected to the shaft 4 by means of a stop mechanism herein shown as of the type more fully described and claimed in the application of G. W. Jacques, Ser. No. 392,200, filed June 28, 1920, the details of which are not herein described, as this mechanism forms no part of the present invention.

In Figs. 7 and 8, is shown a slightly modified construction relating primarily to the mounting of the hopper and related parts. In this construction a bracket 42^a, corresponding to the bracket 42 shown in Fig. 2, carries an extension 421 which supports a hopper 350 having eyelet distributing mechanism actuated through the spiral gear 390, corresponding to the gear 39 shown in Fig. 2. This construction eliminates the arm 33 shown in Fig. 2. A supporting bracket 370 carries the eyelet reservoir 380 in a similar manner to the bracket 37 of the first form, this construction, however, considerably modifying the upper end of the bracket 200 corresponding to the bracket 2 of the other form. In this form a considerable shortening of the machine has been effected by a closer positioning of the actuating cams shown in Fig. 7 at 10^a and 320. In all other respects the parts are the same as before described.

Referring more particularly to Figs. 1 and 3, the inner end of the shaft 4 terminates in a crank pin 50 which carries the follower 51. This follower and a rod 55 form an articulated pitman or connecting-rod for operating the raceway and the presserfoot, and are connected to each other by a pivot member 54. The rod 55 being embraced by a pair of ears 52 and 53 formed on the follower to take the pivot-member. This articulated construction provides for universal angular movement of the rod 55. At its forward end rod 55 has a threaded perforation for the reception of a threaded shank 56 carried by a ball 57, a lock nut 58 retaining the shank in adjusted position lengthwise of the rod 55. At 59 is shown a block which couples and spaces the delivery ends of the raceway sections of the raceway 36, this block having formed therein an open ended socket 60 having a rearward perforation extending through the base thereof through which the shank 56 passes. The socket 60 is internally threaded for the reception of an externally threaded sleeve 61 which has its inner end shaped to fit the ball 57. This ball has a slot 62 opposite

the shank 56 which may be engaged by a screw driver passed through the sleeve 61, and by which it may be turned to adjust the shank 56 lengthwise of the rod 55. The 5 sleeve 61 has a pair of notches diametrically positioned, one of which is shown at 63 in Fig. 3 for the reception of a tool by which the sleeve may be turned within the threaded socket. A lock nut 64, engaging the 10 threads of the sleeve 61 externally of the block 59, locks the sleeve in adjusted position.

Figs. 2, 3, 4 and 9 show means for taking up play of the raceway in consequence of 15 moving the latter to eyelet-presenting position, whereby accurate register of the leading eyelets relatively to the punches is insured. The raceway, at a point near its delivery end, is supported by a fixture 67 and 20 is arranged to slide thereon. The other end of the raceway has pivotal connection (hereinafter described) with the hopper. A radius of this pivotal connection is represented by a broken line extending vertically 25 through the middle of Fig. 9. Rolls 65 and 66 carried by the raceway are arranged to engage opposite edges of the fixture 67 when the raceway is in fastener-presenting position, but when the raceway is retracted from 30 said position they move as indicated by the arrows intersecting them and release their hold on the fixture to give the raceway freedom of movement. They are located at 35 different radii with respect to the axis about which the raceway swings, and are so spaced that the angular movement of the raceway causes them to tighten the raceway relatively to the fixture as the raceway arrives at its eyelet-presenting position.

40 The pivotal connection of the raceway to the hopper is shown in Fig. 2^A. In this figure, 351 represents a plate forming a portion of the hopper. A ball 361 is made fast in the raceway 36 substantially in alignment 45 with the eyelet path, this ball resting in a mating socket 352 in plate 351 to form a universal pivot connection therewith. At 362 is a small roller journaled in an opening 363 in the raceway, this roller projecting slightly above the surface of the raceway and bearing on the under side of plate 351. Between the ball 361 and the roller 362, a slot 364 is cut in the raceway. A pin 363, swaged into plate 351, projects through 50 the slot 364, and slidable thereon is a block 354, somewhat narrower than the slot 364 and projecting within the same. Block 354 carries, off-set from the pin 353, a transverse pin 355, the opposite ends of which engage the lower face of the raceway near its end and out of alignment with the axis of the roll 362 and the ball 361. Pin 353 has threaded on its outer end an adjusting nut 356 and a lock nut 357 to retain the parts in position. With this construction

the raceway is pivoted on the ball 361 for movement from and to eyelet delivery position, this pivot being in line with the eyelet feed so as to offer no obstruction to the same in any position. It is evident that 70 tightening of the nut 356 will, through the upward pressure exerted on the extreme upper end of the raceway, tend to tilt the same about the axis of the roller 362 and ball 361, and thereby press the delivery end downwardly upon the upper surface of guide support 67.

At its outer end support 67 is bifurcated, and between the forks is mounted the shank 68 of a work table having a work supporting plate 69 at its upper end. Shank 68 carries a transverse pin 70 which is seated within aligned notches, one of which is shown at 71 in Fig. 3, in the bifurcated end of the support 67. A leaf spring 72, 80 made fast at 73 to the support 67, is bifurcated at its outer end, where it bears against the pin 70 on either side of shank 68 to retain the work table in position. The support 67 is formed with a reduced extremity 85 90 74 which is adjustably mounted in a bracket 75.

Above the portion 74, and parallel therewith is a similar reduced portion 76 of a support 77, portion 76 also being adjustably fixed in the bracket 75, which is carried by the main frame of the machine preferably from the central bracket 2, as shown in Fig. 2 at 78'. Support 77 is formed similarly to support 67, having a 95 bifurcated forward end, between the forks of which is mounted the shank 78 of a presser foot having a work engaging portion 79. A pin 80 passes through the shank 78 and is seated within a pair of mating 100 depressions, one of which is shown at 81 on Fig. 3, in the forked portion of support 77. A leaf spring 82, fixed in any suitable manner to the support 77, is bifurcated at its outer end and bears against opposite 105 ends of a pin 83 which extends through the shank 78 above the pin 80. A coil spring 800 surrounding an adjusting bolt 801 bears against the upper face of spring 82. Mounted on one side of the support 77 is a small 110 roller 84, and carried by the shank 78 above the pin 83 is a roller 85. A lever member 86, formed at its outer end in a cam portion 87 shown as upwardly turned 115 bears beneath the roll 85, and is fulcrumed on the roller 84. The rear end of rod 86 is adjustably secured in a sleeve 88 by means of a slot and bolt connection therewith shown at 89, the rear end of sleeve 88 being pivoted at 90 to the upper end of the pin 54. As shown in Figs. 2, 4, 5, and 6, shank 68 of the work support is slidably 120 carried in a sleeve 91 pivoted at 92 to the lower hammer element 8, and shank 78 of the presser foot is similarly carried in a 125 130

sleeve 93 pivoted at 94 to the upper hammer element 7.

Referring now to Figs. 3 and 9, each raceway element of the raceway 36 has a forwardly extended open end 100 from which the eyelets may be picked by the corresponding punch in a manner well understood in the art. In order to prevent the eyelets from passing freely from the raceway ends, a lever member 101 is pivoted at 102 to each raceway, and has a forwardly extending finger portion 103 which normally projects partially in front of the opening 100 to obstruct the same. At 104 is shown a rearwardly extending portion of the lever having a slot through which passes a stud 105 threaded at its inner end into the raceway, and having threaded on its other end a polygonal nut 105^a. The portion 104 carries an outwardly extending lug 106 adapted to closely contact with the side of the nut 105^a, and in the position shown in Fig. 9, prevents the latter from being turned. A coil spring 107, surrounding the bolt 105, bears between the raceway and the end 104 of the lever and normally retains the same in the position shown in Fig. 9 with the finger 103 obstructing the passage of eyelets. It is evident that an eyelet can be forcibly removed from the opening 100 against the force of the spring 107 which allows the finger 103 to yield, and that by turning the nut 105^a the degree of obstruction offered by the finger 103 can be regulated. The lug 106 normally prevents such turning of the nut 105^a, but by depression of the end 104 of the lever, this lug is retracted from contact with the nut whereupon it may be turned, this position of the lever, however, being abnormal and not reached in the normal operation of the machine when the eyelets are forcibly removed from the raceway ends.

The operation of the above described mechanism is as follows:

Two pieces of material are placed in superposed relation between the presser foot and work support elements 79 and 69, and are brought into position one on either side 50 of the anvil 17. The parts are now in the relative positions shown in Fig. 4. When the machine is put into operation, the hammer elements 7 and 8 force the punch and set elements toward the anvil to punch the work. In this position of the parts the raceways support the two leading eyelets in register with the punches which pass through said eyelets. In the further operation of the machine the raceway is drawn 60 rearwardly by crank 50 away from the punches, which pull the threaded eyelets from the raceway, the fingers 103 yielding to release the eyelets. Further movement of the punches causes the punching of the material, and the crank 50, acting on the

lever 86, rocks the same about the roller 84 and moves it bodily to the rear so that the lever acts on the roll 85 to lift the presser foot from the work, the position of these parts being then as shown in Fig. 5. While 70 the punches are in engagement with the work, cam 32, actuating the feed mechanism, swings the feed frame to the left as shown in Fig. 2, or in the direction of the arrow on Fig. 5. At or near the end of the feed motion the hammer elements 7 and 8 actuate the sets to set the eyelets, already threaded on the punches, whereupon the hammer elements retract the punches and sets from the material. As this action is taking place, 80 crank 50 moves the lever 86 forwardly, allowing the presser foot to again engage the material, the parts being then as shown in Fig. 6. The feed frame then begins its return motion preparatory to a succeeding 85 punching operation at which time also the raceway has again been moved by crank 50 to place the new leading eyelets in register with the punches.

It is to be understood that the pressure 90 of the presser foot on the work is relieved prior to and during the feeding period to avoid counter-drag, and also that the confronting work elements are held in contact in advance of the punching and setting localities during the entire action of the machine, and clamped by the presser foot while the feed frame is returning, at which time the punches and sets are out of engagement with the work.

Having thus described certain embodiments of this invention it should be recognized that various modifications and changes might be made therein without departing from its spirit or scope as defined 105 by the appended claims.

I claim:

1. In a fastener setting machine, fastener setting instrumentalities, a raceway movable to present fasteners to said instrumentalities 110 and then to retract therefrom, a work table, a presser foot normally engaging work on said table, a shaft, an actuating element thereon, a follower therefor, and independent connections therefrom for moving said raceway and lifting said presser foot from the work.

2. In a fastener setting machine, fastener setting instrumentalities, a raceway movable to present fasteners to said instrumentalities 115 and then to retract therefrom a work table, a presser foot normally engaging work on said table, a drive shaft, means actuated by said shaft for actuating said instrumentalities to punch, feed and set fasteners in the work, an actuating element on said shaft, a follower therefor, and mutually independent connections therefrom for moving said raceway and for lifting said presser foot from the work.

3. In a machine having fastener-setting mechanism, mechanism for feeding the work step by step, and an operating shaft, a combination comprising fastener-supplying mechanism operable by said shaft, means for clamping the work between feeding steps, and means operable by an element of said fastener-supplying mechanism to prevent said clamping means from exercising its clamping action during the work-feeding periods. 70
4. In a machine of the class described, a feed frame, an anvil carried by said frame, a pair of punches carried by said frame and cooperating with opposite sides of said anvil, means to actuate said punches to punch a pair of pieces of material passing either side of said anvil, means to move said frame to feed the material while the said punches are in engagement therewith, means to clamp the pieces of material together adjacent said frame, and means to automatically hold said clamping means unclamped during the feed of the material. 75
5. In a machine of the class described, a feed frame, an anvil carried by said frame, a pair of punch and set devices carried by said frame and cooperating with opposite sides of said anvil to punch two pieces of work one on either side of said anvil and to set fasteners in the holes so punched, means to move said frame while said devices are in contact with the material to feed the same, raceways movable to deliver fasteners to said devices and to retract therefrom, means to clamp the two pieces of material together adjacent said devices, and an element for moving said raceway and for holding said clamping means unclamped during the feed of the work. 90
6. In a machine of the class described, a feed frame, an anvil carried by said frame, a pair of punch and set devices carried by said frame and cooperating with opposite sides of said anvil to punch two pieces of work one on either side of said anvil and to set fasteners in the holes so punched, means to move said frame while said devices are in contact with the material to feed the same, raceways movable to deliver fasteners to said devices and to retract therefrom, a work table over which both pieces of material are fed in superposed relation, a presser foot engaging the material and clamping it against said table, and an element for moving said raceways and for holding said presser foot raised from the material during the feed of the same. 95
7. In a machine of the class described, a feed frame, an anvil carried by said frame, a pair of punch and set devices carried by said frame and cooperating with opposite sides of said anvil to punch two pieces of work one on either side of said anvil and to set fasteners in the holes so punched, 100
- means to move said frame while said devices are in contact with the work to feed the same, a work table over which the pieces of work are fed in superposed relation, a presser foot bearing resiliently against the upper piece of material and clamping both pieces against said table, and means for automatically holding said presser foot raised during the feed of the work. 105
8. In a machine of the class described, fastener setting devices, a raceway movable to present fasteners to said devices and to retract therefrom, a work table for supporting work presented to said devices, a presser foot for clamping the work against said table, a rotary actuating element, a follower therefor, and mutually independent connections therefrom for moving said raceway and for periodically raising said presser foot from the work. 110
9. In a machine of the class described, fastener setting devices, a raceway movable to present fasteners to said devices and to retract therefrom, a work table for supporting work presented to said devices, a presser foot for clamping the work against said table, an actuating shaft, an eccentric member on said shaft, a follower for said eccentric member, connections from said follower to move said raceway, and connections from said follower to periodically lift said presser foot. 115
10. In a machine for effecting a manufacturing result on material, a work table, a presser foot for clamping work against said table, a rotary shaft, a fixed fulcrum, a lever vibratory and endwise movable upon said fulcrum for periodically raising said presser foot from the work, and means connected with said shaft for imparting to said lever 120 its endwise and vibratory movements. 125
11. In a machine for operating on material, a work table, a presserfoot for clamping material to be operated upon against said table, and presserfoot-operating mechanism including a rod arranged to execute longitudinal movement relatively to said presserfoot and angular movement to retract the presserfoot from said table. 130
12. In a machine for effecting a manufacturing result on material, a work table, a presser foot for clamping work against said table, a rotary shaft, a bodily movable and rocking cam member for periodically raising said presser foot from the work, and means connected with said shaft for imparting operative movements to said cam member. 135
13. In a machine for effecting a manufacturing result on material, a work table over which the work is fed, a support, a presser foot carried by said support and engaging work on said table, a spring urging said presser foot toward said work table, a fulcrum member on said support, 140

an element on said presser foot, a shaft, an eccentric member on said shaft, and a rod slidably engaging said fulcrum member and said element to periodically raise said presser foot on the rotation of said shaft.

14. In a fastener-inserting machine having work-clamping means and a punch that feeds the work relatively to said means, the combination comprising a rotary shaft, an

actuator carried thereby, fastener-supplying mechanism, and connections arranged to be actuated by said actuator to operate said fastener-supplying mechanism and said clamping means.

In testimony whereof, I have signed my name to this specification.

GEORGE W. JACQUES.
